UNITED STATES PATENT OFFICE.

THOMAS P. BROOKE, OF CHICAGO, ILLINOIS, ASSIGNOR, BY MESNE ASSIGNMENTS, OF ONE-FOURTH TO FRANKLIN A. UMSTED, OF CHICAGO, ILLINOIS.

INTERNAL-COMBUSTION ENGINE.

1,196,840.

Specification of Letters Patent. Patented Sept. 5, 1916.

Application filed August 5, 1911. Serial No. 642,556.

To all whom it may concern:

Be it known that I, THOMAS P. BROOKE, a citizen of the United States, residing at Chicago, county of Cook, and State of Illinois, have invented certain new and useful Improvements in Internal-Combustion Engines, of which the following is a full, clear, and exact specification.

This invention relates to internal combustion engines, and more particularly to the valve mechanism of that type of engine which is so constructed that the cylinders revolve around a common center and the valves are counter-weighted to prevent the centrifugal force thus created from unduly influencing them in their opening or closing movements; and the invention has for its object to provide an improved engine of this type in which the valves shall be positively controlled by a regularly moving part of the engine.

The invention consists in the features of novelty in the construction, combination and arrangement of parts shown in the accompanying drawings, described in the specification, and particularly pointed out in the claims.

In the said drawings which show an example of the invention, Figure 1 is an axial elevation of an engine embodying this invention, partly in section on a plane extending longitudinally of one of the cylinders; Fig. 2 is an enlarged detail sectional view of the valve mechanism and associated parts; Fig. 3 is another sectional view thereof taken on the irregular line 3—3, Fig. 2; Fig. 4 is a section at right angles to the plane of the section of Fig. 2, on the line 4—4 Fig. 2; Fig. 5 is a section on the line 5—5 Fig. 2, and Fig. 6 is a detail section on the line 6—6 Fig. 5.

An engine of the same general type to which this invention is applied constitutes the subject matter of the claims in my co-pending application, Serial Number 588,578 filed October 24th, 1910. Generally speaking, the same embodies a plurality of revolving radially arranged engine cylinders 7, mounted upon a crank case 8, which is suitably journaled on a fixed crank shaft 9, having one or more cranks 10 provided with crank pin 11, to which all of the piston rods 12 of the various cylinders are individually pivoted in the usual or any suitable way, the crank pin 11, of course, being

immovable with relation to the shaft 9, and constituting the center about which all the pistons 13 and their piston rods swing while the cylinders revolve about the shaft 9 as their common center, thereby resulting in a relatively reciprocating movement of piston and cylinder. The outer ends of the cylinders may be provided with exhaust valves 14, controlled by means well known in the art, or in any suitable way, not necessary to illustrate, and this end of the cylinder may also be provided with an igniter 15.

In the head or end of the piston is secured a valve cage embodying a valve seat 16, in which is formed a spider 17 constituting a guide for the stem 18 of valve 19, the stem having a flange 20 secured to or formed thereon for the support of the spring 21, which serves to keep the valve closed while starting. This valve 19 is an intake valve, and serves to control the intake port in the head of the piston in which the valve seat 16 is secured. The combustible mixture or other fluid element for making the charge is admitted first to the crank case 8 through any suitable passage, not necessary to illustrate, and as the piston 13 undergoes a relatively inward movement, this fluid in the crank case escapes through the intake port in the piston head past the valve 19, and becomes entrapped between the piston and outer end of the cylinder when the piston and cylinder make a relatively approaching movement according to the well known principle of the four stroke cycle internal combustion engine.

In my former application I have shown and described weights arranged to act upon the valve 19 in order to counter-balance the centrifugal force generated in the valve by the revolving movement of the cylinders and pistons. Similar weights are also employed in connection with the present invention. These are shown at 22—23, and have arms or levers 24 pivoted on pins 25, and arranged to engage the flange 20, so that the centrifugal force generated in the weights 22—23 will cause them to move outwardly, and thereby induce the inner ends of the levers 24 to pull the valve 19 toward its seat and overcome the centrifugal force generated in the valve, the valve being opened in my said former invention by the difference in atmospheric pressure created on opposite sides of the piston head due to the dis-

placement of the fluid contents of the cylinder by the relative movement of piston and cylinder; or by the force of the compressed fluid in crank case; but in practice it is found that something more positive than this force is required for inducing the valve to unseat at the proper time. To that end, the valve, according to this invention, is provided with means positively operated from a regularly moving part of the engine, for subjecting it to a requisite degree of force at the proper time for unseating it and relieving it of this force at the time when it should close or commence to close. Specifically, the devices which have been adopted for this purpose consist of a weight so related to the valve that the centrifugal force generated in the weight will be imposed upon the valve during the period the valve should be open, and a cam or moving member connected with the piston rod for pulling the weight inward when it is time for the valve to close. This weight is in the form of a yoke having three branches 27—28—29, constituting a substantially U-shaped member, the branches 27—28 of which project outwardly through suitable guide passages 30 in the spider 17 of the valve cage, whereby the outer ends of these branches will be guided while making their reciprocatory movements toward and from the inner face of the valve. When not otherwise restrained during the operation of the engine, the centrifugal force generated in the weight 27—28—29 is thus imposed upon the valve, and it is thereby forced from its seat. When it is time for the valve to close the weight is moved in the opposite direction by a cam 31, connected with the piston rod 12, in such a way as to receive a rocking action therefrom and cause it to impinge against the branch 29 of the weight in the manner shown in Fig. 3. This cam is also provided with side flanges 32, which engage with the sides of branches 28—29 for holding the inner end of the weight 27—28—29 against movement transverse to the plane of oscillation of cam 31, while movement parallel with the plane of oscillation of cam 31 is prevented by the curved face 33 of the cam engaging branch 28, and the hub 34 of the cam engaging branch 27, also by the guides 30. The cam 33 is rigidly secured to the piston rod 12. This is accomplished by any suitable expedient. The hub 34 of the cam is embraced by two branches 35 of the piston rod 12, and brazed or otherwise secured thereto. This hub is journaled upon a gudgeon pin or pivot 36, rigidly secured at its ends in two hangers 37, depending from the sides of the valve seat member 16. These hangers 37 are provided with openings 38, through which the levers 24 project, and in which the pivots 26 are situated.

5 In the operation of the engine it will, of course, be understood that as the cylinders and pistons revolve about different centers, the angular relation of the piston rods and cylinders is continually changing, and thereby resulting in a rocking action of the cam 31 in each cylinder with relation to its weight 27—28—29, and the cam is so proportioned and arranged with relation to the parts by which it is operated and those upon which it operates that it will recede from the branch 29 of the weight when the piston starts its stroke relatively toward the center 9, and in a four cycle engine, although this stroke occurs twice during each cycle, the valve will be forced open only during the suction stroke, because during the other stroke it is held to its seat by the force of the explosion; and as the suction stroke is completed, or about to be completed, the piston being at or near the extremity of its stroke toward the center 9, the cam 31 comes against branch 29 and relieves the valve of the weight 27—28—29, permitting it to be closed by the spring 21, or by the centrifugal force acting on the counter-weight.

10 I claim:

1. In an internal combustion engine, the combination of a plurality of cylinders revolving about a common center, a plurality of pistons for said cylinders respectively revolving about a different center, valves for controlling the fluid contents of said cylinders revolving therewith, and counterweighted to resist the tendency of the centrifugal force generated therein to open them, a piston rod connected with each of said pistons and adapted to oscillate with relation thereto as the cylinders and pistons revolve, a weight movable independently of the valve in each cylinder for aiding in the unseating of the valve, and a projection connected with said piston rod and arranged to engage and control said weight to relieve the valve of the force thereof during the compression stroke of the piston.

15 2. The combination of an internal combustion engine having revolving cylinders and reciprocable valved pistons with oscillating piston rods, of a yoke member operatively related to each piston valve, and a cam member fixed to oscillate with the piston rod and adapted to engage the yoke to positively close the valve during the outward movement of the piston.

3. An internal combustion engine having a revolving cylinder, a reciprocating valved piston and an oscillating piston rod, a yoke operatively related to the valve, a cam moved with the piston rod to close the valve during the outward movement of the piston, and pivoted counterweights to engage and balance the valve during its outward movement.

20 4. An internal combustion engine having a revolving cylinder, a reciprocating valved

piston and an oscillating piston rod, a yoke operatively related to the valve, a cam moved with the piston rod to close the valve during the outward movement of the piston, 5 pivoted counterweights to balance the valve only during its outward movement, and a seating spring for the valve.

5. In an internal combustion engine having a revolving cylinder, a reciprocating valved piston and an oscillating piston rod, the combination of a yoke operatively related to the valve, a flange secured to the valve stem, counterweights pivoted in the valve adapted to engage the flange and bal-

15 ance the valve only during its inward movement, and a cam secured to and movable with the piston rod as it oscillates to positively close the valve only during the outward movement of the piston in the cylinder.

20 In testimony whereof I have signed my name to this specification, in the presence of two subscribing witnesses, on this 3rd day of August, A. D. 1911.

THOMAS P. BROOKE.
